THE NORRIS PETERS CO., PHOTO-LITHO., WASHINGTON, D. C.

UNITED STATES PATENT OFFICE.

LESTER I. COONRADT, OF CHICAGO, ILLINOIS.

AUTOMATICALLY-OPERATING WEATHER-STRIP.

1,111,737.

Specification of Letters Patent. Patented Sept. 29, 1914.

Application filed September 30, 1912. Serial No. 723,040.

To all whom it may concern:

Be it known that I, LESTER I. COONRADT, a citizen of the United States, and a resident of the city of Chicago, in the county of Cook, and State of Illinois, have invented certain new and useful Improvements in Automatically-Operating Weather-Strips; and I do hereby declare that the following is a full, clear, and exact description of the same, reference being had to the accompanying drawings, and to the numbers of reference marked thereon, which form a part of this specification.

It has heretofore proven difficult, in fact, well nigh impossible to afford a weather strip or guard satisfactory for use at the bottom or top of doors, windows, or the like, owing to the fact that slight settlement of a building frequently results in the top or bottom of the door or window becoming non-parallel with the threshold, sill, or head of the frame. The same difficulty is frequently experienced with sliding doors, where slight settlement or sagging of the lintel upon which the doors may slide, may be sufficient to produce imperfect fitting, and afford spaces very hard to seal or weather proof with the weatherproofing heretofore used.

The object of this invention is to afford a construction adapted for quite general use, by means of which effective weatherproofing is secured, even though the door or window fit very loosely in the frame or threshold and the top and bottom of the door or window are not parallel.

It is an object of the invention to afford a construction capable of adapting itself automatically to the frame or sill to insure effective sealing.

It is an object of the invention also to afford a construction or mechanism adapted to be projected into operative position automatically with the closing of the door or window.

The invention (in a preferred form) is illustrated in the drawings, and hereinafter more fully described.

In the drawings: Figure 1 is a fragmentary perspective view of a swinging door equipped at the bottom with weather proofing embodying my invention. Fig. 2 is a fragmentary transverse section thereof. Fig. 3 is a fragmentary detail, partly in section, and taken at the bottom of a door to illustrate the installation. Fig. 4 is an enlarged fragmentary detail, with the casing

of the weather strip in section, and illustrating the operation. Fig. 5 is an enlarged, fragmentary section similar to Fig. 3. Fig. 6 is a transverse section taken through the bottom of the door and weather proofing device. Fig. 7 is a section similar to Fig. 3, but illustrating a modified construction. Fig. 8 is an enlarged section on line 8 of Fig. 7. Fig. 9 is a fragmentary rear edge view of a door, illustrating the construction in which the weather proofing is seated in a groove in the bottom of the door. Fig. 10 is an enlarged similar view, but illustrating the attachment of the weather proofing device to the face of the door.

As shown in the drawings: 1, indicates the door; 2, the door jamb, having seated therein a striking plate A, for the actuating means for the weather strip. As shown in Figs. 1 to 6 inclusive, my improved weather strip or weather proofing device, is seated in a suitable groove in the door bottom, and comprises a sheet metal channel 3, which affords a container for the device, and the web 4 of which, forms the inner wall of the containing chamber when said channel is in place. One or more sleeves 5, are provided in the top of said channel, and slidably extending therethrough is a thrust rod 6, on the end of which, protruding through the hanging rail of the door, is threaded an adjustable striking cap 7, for engagement with the striking plate A, before described, whereby said rod is shifted longitudinally in the channel and transversely of the door by being pressed inwardly when the door is closed. Stops 8 and 9, are rigidly secured on said rod, the one at its outer extremity, the other near the opposite end thereof, as shown in Figs 3 and 4, and slidably engaged on said rod are blocks 10, each provided with an oblique downwardly directed slot or cam groove therein, as shown, the lower ends of which are directed rearwardly or toward the hanging stile of the door. Engaged on said rod which extends therethrough, are coiled springs 11, which press against the rear edge of the cam blocks 10, and the rear ends of the springs are engaged by a stop 12, rigidly secured on the push rod 6, before described, so that inward movement of the push rod tends to move said cam blocks therewith. Fitting into the channel 3, and receiving said cam blocks 10, thereinto, is a channel bar 13, which may be constructed of any suitable metal, and which

is provided with pins 14, each equipped with a roller 15, which fits in the slot or cam groove in said cam blocks.

Seated in the front and rear edges of the door, are end plates 16 and 17, through the latter of which the striking projection on said rod extends. The channel 13, may be provided at its ends with rollers A', to bear against the inner sides of said end plates, or may itself bear against said end plates, and is hence held from longitudinal movement thereby, but is free to be actuated transversely the bottom of the door or window by the actuation of the rod 6. As shown, the web of the channel is formed or rolled to afford a recess therein to receive a strip 18, of felt, rubber or any suitable material to seal the joint.

The constructions illustrated in Figs. 7 and 8, are quite similar; the channel 3, such as before described, is likewise embedded in a suitable groove in the bottom of the door, but the springs are differentially disposed. In this construction, a tubular extension 19, is connected with the casing and extends upwardly into a suitable recess therefor in the door, and mounted in each is a coil spring 20. The thrust rod 21, corresponds with the rod 6, before described, and is likewise provided with a striking and adjusting cap 7. The sealing bar 22, is provided with a groove in its bottom to receive a strip 23, of rubber or other suitable material adapted to close on the surface opposed thereto at the floor or frame. A rod 24, is engaged in the sealing bar and extends upwardly through the spring. Positively engaged with the upper end of said rod and with the upper end of the spring through which the same extends, is a cable 26, the lower end of which is connected with one end of a coil or spiral spring 27, the other end of which is connected on the thrust rod 21, remote from the striking head 7. End plates 16 and 17, are provided as before described, which serve to limit and hold said sealing bar from longitudinal movement, as before described.

The operation is as follows: Referring first to the construction shown in Figs. 1 to 6 inclusive, the closing of the door acts to force the thrust rod 6, inwardly, shifting the cam blocks thereby therewith, and inasmuch as the channel 13, is held from longitudinal movement, said channel bearing the sealing strip 18, is forced outwardly and into bearing engagement with the adjacent opposed surface of the frame or floor. Should the floor, sill or frame not be parallel with the edge of the door or window to be sealed, said sealing strip is nevertheless forced firmly and uniformly thereagainst, inasmuch as the cam block adjacent the narrowest portion of the crack or opening will soon come to rest, whereupon the spring 11, adjacent

that end of the strip is compressed slightly or sufficiently to equalize the sealing bar or strip perfectly to the threshold or that which is engaged thereby. When the door is again opened, the spring 28, which is of less strength than the spring 11, and which bears against the sleeve 5, at its inner end and against a stop 29, secured on the thrust rod 6, at its outer end, acts to return the thrust rod to normal position, the stops 8 and 9, on said rod, picking up said cam blocks and retracting the weather strip thereby.

The operation of the strip indicated in Figs. 7 and 8, is substantially the same. The springs 27, permit independent adjustment of opposite ends of the sealing or weather proofing strip to enable the same to fit to the sill or threshold and when the door is opened, said springs together with the springs 20, act to return the thrust rod to normal position.

Of course, it is not necessary that the weather-proofing device be seated in a groove in the edge of the door or window, for obviously the same may be contained within a suitable casing such as 30, indicated in Fig. 10, and screwed or bolted to the face of the door or window where required, as preferred. If used in connection with a sliding window, of course, a suitable projection is provided on the frame to engage the striking head and press the same inwardly as the same is closed.

Details of construction and operation may vary through a wide degree. I have merely shown and described a preferred form of the invention, and I do not purpose limiting the patent granted on this application for patent otherwise than necessitated by the prior art.

I claim as my invention:

1. In a device of the class described, a door, a casing disposed longitudinally of the base thereof, a sealing member slidable vertically in said casing, vertical rods secured on said sealing member, springs engaging said rods for retaining said sealing member normally retracted, a longitudinally movable rigid thrust bar guided to move in a straight line, and flexible connections between said thrust rod and said vertical rods for projecting said vertical rods and said sealing member when said thrust rod is moved longitudinally.

2. In a device of the class described, a door, a casing disposed longitudinally of the base thereof, a sealing member slidable vertically in said casing, tubular extensions extending upwardly from the top of said casing, rods secured on said sealing member and extending vertically into said tubular casings, springs interposed in said tubular members for engaging said rods and normally retaining said sealing member re-

tracted, a longitudinally movable rigid thrust rod guided to move in a straight line, and flexible connections between said thrust rod and said vertical rods for projecting 5 said vertical rods and said sealing member when said thrust rod is moved longitudinally.

3. In a device of the class described, a door, a casing disposed longitudinally of the 10 base thereof, a sealing member slideable vertically in said casing, vertical rods secured on said sealing member, springs engaging said rods for normally retaining said sealing member retracted, a longitudinally mov-

able rigid thrust rod, and spring and cable 15 connections between said thrust rod and said vertical rods, said cable springs being stronger than said vertical rod springs whereby said sealing member will be yieldingly projected by the longitudinal movement of said thrust rod.

In testimony whereof I have hereunto subscribed my name in the presence of two subscribing witnesses.

LESTER I. COONRADT.
